WALTER L. CONWELL, OF MONTCLAIR, AND ALLEN EDWARD OSTRANDER, OF RIDGEWOOD, NEW JERSEY, ASSIGNEES TO TRANSPORTATION UTILITIES COMPANY, OF NEW YORK, N. Y., A CORPORATION OF WEST VIRGINIA.

RAILWAY-CAR DOOR.

1,089,398.

Specification of Letters Patent. Patented Mar. 10, 1914.

Application filed July 8, 1913. Serial No. 777,842.

To all whom it may concern:

Be it known that we, WALTER L. CONWELL and ALLEN E. OSTRANDER, residing at Montclair, Essex county, New Jersey, and Ridgewood, Bergen county, New Jersey, respectively, and being citizens of the United States, have invented certain new and useful Improvements in Railway-Car Doors, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is an elevational view of a fragment of a car side equipped with a door having door fixtures formed and attached to the door as contemplated in accordance with the present invention. Fig. 2 is a vertical sectional view taken on line 2—2 of Fig. 1. Fig. 3 is a vertical sectional view taken on line 3—3 of Fig. 1. Figs. 4 and 5 are horizontal sectional views taken, respectively, on lines 4—4 and 5—5 of Fig. 1. Fig. 6 is an edge view of the hanger showing the lugs 10 extending laterally from the body of the hanger.

The object of the invention is to provide a door formed of sheet metal of light weight, which is reinforced by means of corrugations extending vertically and horizontally, and is especially intended for use in car construction, though the door is adapted to other purposes.

One of the objects of the invention is to utilize the door fixtures as means for securing together the sheets forming the doors.

Another object is to provide fixtures of such contour that parts of the fixtures will rest within channel portions of the corrugations in one face of the door in such manner that torsional disturbances of the connected fixtures and door will be avoided.

Other objects of the invention are economy of manufacture and utilization, with but slight changes in details of formation, of standard fixtures which are well known in the art.

Primarily, the invention consists of par-

allel, substantially conterminous corrugated sheets of metal of light weight, in which the corrugations are disposed at right angles and the sheets are connected at their edges by suitable rivets or other securing means, and are connected within the edges by means of door fixtures intended to be used for supporting, locking and guiding the door, which fixtures are so disposed with relation to the corrugations that the contour of parts of the fixtures is utilized to prevent displacement, in addition to which the fixtures are secured to the corrugated sheets of the door by means which connect such sheets together and reinforce the part of the door within the zone of connection of fixtures to the door.

Referring specifically to the drawings, A indicates the door which, as will be noted in the sectional views Figs. 2, 3, 4 and 5, is composed of parallel sheets B and C, which sheets B and C are provided with corrugations intersecting at right angles and comprising channel portions D and ribs E, which ribs outline the channels. The fixtures comprise door hangers, door locking means and the handle for shifting the door. These parts are secured to the outer face of the door, as is common in car construction.

Referring specifically to the hanger, it will be noted that said hanger is provided with a bracket 1, an upward extension 2, terminating in an inset portion 3, carrying a supporting wheel or roller 4 and with an integral guide finger 5, and that the track portion for the hanger is provided with an upper flange 6, a vertical web 7, a horizontal flange 8 and a depending vertical flange 9, on the horizontal flange 8 of which the roller 4 travels and the flange 9 laps the upper edge of the door, while the finger 5 of the hanger is interposed between the door and the flange 9.

The bracket portion 1 of the hanger is provided with integral perforated spaced lugs 10, which lugs are spaced vertically and horizontally, as shown in Fig. 6, so that said lugs will occupy and substantially fill the channels D in the face of the door in which they rest, the remaining portions of the hanger lapping the door and extending upwardly above the same as shown.

It is evident that with a door suspended from above by means of hangers of the type

shown, there is a considerable degree of torsion on the hanger, and when rivets alone are used as securing means to connect the hanger to the door there is a probability of the rivets working loose, which would result in some lost motion. Owing to the thin metal of which the door proper is composed, this tendency is materially increased, hence it is desirable to protect the connection of the door hanger to the door to avoid such torsional disturbance. This is accomplished by the lugs of the hanger which rest within the channels D, substantially filling said channels, whereby the outstanding ribs E on the outer face of the door will serve as side abutments for the lugs, and to better assist in preventing such torsional disturbance the lugs are spaced apart vertically, the grip of the lugs being assisted by such vertical spacing and by the horizontal spacing shown, so that more than one vertical channel D is occupied by the lugs. It is evident that the horizontal and vertical spacing thus assists in holding the door hanger in position. The vertical spacing of the lugs is indicated because the door hangers are formed of cast metal, which can be better formed with lugs spaced apart both vertically and horizontally as shown, though it is evident that the vertical lugs may be connected by an intermediate web, if desired, though where the bracket is made of malleable iron the lugs may be better annealed when they are formed separately as indicated.

The locking fixture is secured to the door in substantially the same manner as the door hanger bracket, and said locking fixture comprises the plate 20, which is provided with the integral horizontally spaced lugs 21, which, like the lugs of the door hanger, are perforated. The plate 20 has co-operating with it a supplemental locking plate 22, which is connected by hooked engagement with the plate 20, a hooked end 23 engaged with the perforation 20^a of the plate 20, as shown in Fig. 4, and rivets 25 secure the locking plate in position, the same rivets securing the plate 20 to the door, thereby providing a recess between said plates for the ring 25 of the hasp 26.

It is understood that the hasp extends beyond the edge of the door and is adapted to interlock with a suitable stud 30, the usual door sill being employed for that purpose.

The handle on the outer side of the door, by means of which the door is shifted, is of the conventional form, comprising the loop 31, which, like the door hanger bracket and the hasp plate, is provided with inwardly extending studs 32, which studs are perforated for the passage of the rivets 33, adapted to secure said handle in position.

As will be noted in the drawings, the studs 32 are arranged in pairs, one pair at each

end of the door handle and the members of each pair being arranged vertically so as to occupy proper positions within the vertical channels in the outer face of the door.

A feature common to the door hanger, 70 hasp plate and to the handle is means to prevent rupture of the thin metal plates forming the door, this feature consisting of a bar or series of bars 35, resting within the horizontal channels on the inner side of the door and extending far enough horizontally to receive the horizontally spaced rivets of the door hanger, one of the bars 35 being disposed at the middle portion of the hanger bracket and another of the bars being disposed near the lower portion of the bracket, as best shown in the sectional view Fig. 2.

The hasp plate is likewise reinforced in its connection to the door by means of a bar 35^a, which, as shown in Fig. 4, has sufficient length to receive through it the four rivets shown as connecting the hasp plate to the door. Likewise the handle 31 is connected to the door, the rivets 33 extending through horizontally disposed bars 35^b.

It is to be noted that the bars 35, 35^a and 35^b are suitably perforated for the passage of the securing rivets, and said bars are of substantially the width vertically of the horizontal channels on the inner face of the door, within which said doors are positioned. Thus, it will be apparent that while the door fixtures are connected with the doors by direct rivet connection through the thin metal plates comprising the doors, such metal plates are reinforced within the zone of connection by means of the reinforcing bars indicated and rupture of the sheet metal of the doors is effectually prevented. Suitable back stops, as 37, may be employed and bottom guides, 38, are provided for the lower edge of the door, as is common in car doors.

We claim:

1. In a railway car door, vertically disposed corrugations on the outer face thereof, a door hanger extending above the upper edge of the door and extending downwardly and lapping certain of said vertical corrugations and interlocked with the door against torsional stresses by means of lugs projecting from the hanger inwardly within a channel formed by said corrugations and in juxtaposition to and between outwardly extending ribs outlining said channels, and fixture securing means projected through said lugs and through the door.

2. In a railway car door, vertically disposed corrugations on the outer face thereof, a door fixture lapping certain of said vertical corrugations and interlocked with the door against torsional stresses by means of hollow lugs projecting from the fixture inwardly within channels formed by said corrugations and in juxtaposition to and be-

- tween outwardly extending ribs outlining said channels, and fixture securing means projected through said hollow lugs and through the door.
5. 3. In a car door, relatively parallel corrugated sheets of metal secured together with the corrugations of the parallel sheets right angularly disposed, in combination with a door fixture lapping a plurality of 50 extending ribs or projecting faces of said corrugations and having spaced perforated lugs inset within recesses or channel portions of a plurality of corrugations, and a plurality of rivets extending through said 55 spaced perforated lugs and the parallel sheets of the door to secure the fixture to the door and securing the parallel corrugated sheets together.
4. In a railway car door, vertically disposed corrugations on one face thereof, horizontally disposed corrugations on the other face of the door, a door hanger extending above the upper edge of the door and extending downwardly and lapping the door 60 20 and interlocked with the door against torsional stresses by means of extensions projecting from the hanger partly within spaced channels formed by said corrugations on one face and in juxtaposition to and between 65 25 outwardly extending ribs outlining said channels, a reinforcing member in a channel on the other face of the door, and securing means projected through said hollow lugs through the door and through said reinforcing member.
5. In a railway car door, vertically disposed corrugations on one face thereof, horizontal channels on the opposite face of said door, a door fixture lapping the door and 70 30 interlocked with the door against torsional stresses by means integral with said fixture projecting from the fixture within channels formed by said corrugations and in juxtaposition to and between extending ribs outlining said channels, a reinforcing bar in one 75 35 of said horizontal channels, and fixture se- 40 45 curing means projected through said door fixture through the door and through said bar.
6. In a car door, relatively parallel corrugated sheets of metal secured together with the corrugations of the parallel sheets right angularly disposed, in combination with a door fixture lapping a plurality of extending ribs or projecting faces of said corrugations and inset within recesses or channel portions of a plurality of corrugations, of one side of said door, a reinforcing member set in a channel portion of the opposite face of the door, and a plurality of rivets extending 60 50 through said spaced perforated lugs, through the parallel sheets of the door to secure the fixture to the door and securing the parallel corrugated sheets together, and through said reinforcing member to reinforce the connection to the door.
7. In a car door, relatively parallel corrugated sheets of metal secured together with the corrugations of the parallel sheets right angularly disposed vertically and horizontally, in combination with a door fixture lapping a plurality of extending ribs or projecting faces of said corrugations and having spaced perforated extensions inset within recesses or channel portions of a plurality 75 55 of corrugations, a reinforcing perforated member inset at the opposite face of the door, and a plurality of rivets extending through said spaced perforated extensions, through the parallel sheets of the door and 80 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300
